2,465,256

GASEOUS DISCHARGE TUBE

Johannes Gijsbertus Wilhelm Mulder, Eindhoven,
Netherlands, assignor to Hartford National
Bank and Trust Company, Hartford, Conn., as
trustee

Application April 29, 1946, Serial No. 665,662
In Belgium February 8, 1945

Section 1, Public Law 690, August 8, 1946
Patent expires February 8, 1965

6 Claims. (Cl. 250—27.5)

1

This invention relates to a rectifier tube with gas or vapour filling and comprising an incandescent cathode.

Of such tubes, more particularly of those comprising an activated incandescent cathode, the period of life is materially reduced because, when the tube is switched in with cold cathode and full anode voltage, the arc voltage during the heating-up period of the cathode is so high that the incandescent cathode is readily deteriorated. Under these conditions the risk of arc-back is also abnormally great.

It is already known to switch on the anode voltage automatically only when the cathode has attained a determined temperature or at least has been heated up during a given period of time but since the automatic switches required for this purpose must be designed for the full anode current, they are bulky and expensive.

In the rectifier tube with gas or vapour filling according to the invention the incandescent cathode is surrounded by a shield, owing to which the operating voltage is in practice not higher than it would be in a large tube with equal pressure and equal distance between the electrodes without the shield whilst in front of the aperture or apertures for the passage of the discharge there is provided in association with the shield an auxiliary electrode by which the operating voltage is not increased to any appreciable extent and which is shaped and placed in such manner that with floating potential of the cathode shield and of the auxiliary electrode the igniting voltage of the tube is higher than the anode voltage. The tubes involved are those whose cathode shield has so little influence on the operating voltage that the latter is at the most 25% higher than the lowest possible operating voltage with equal pressure and equal distance between the electrodes without shield. The auxiliary electrode causes a considerably smaller increase of the operating voltage, which is in most cases not higher than 1 volt. The term "igniting voltage" is to be understood to mean the first igniting voltage of the tube after switching in. This voltage is in most cases higher than the re-igniting voltage if the tube is operated on alternating current. By suitably biasing the cathode shield and the auxiliary electrode the tube is ignited at the normal igniting voltage. The cathode shield and the auxiliary electrode may be connected, for example, in common or separately through a large resistance or a rectifier to the anode. As an alternative, they may be connected jointly to one point or separately to two points of a potentiometer interposed between the anode and the cathode. Since the cathode shield and the auxiliary electrode are traversed by a but small current only a small automatic switch is required which is not

2

larger than a telephone relay so that the switch may consequently be inexpensive and of small size as compared with the automatic switches formerly used in the anode lead.

5 Tubes are also known which require an auxiliary ignition but in this case these are tubes which have a high operating voltage as a result of additional screens or anode arms.

It is very simple to manufacture the auxiliary 10 electrode from wire or band and to form it in the same shape as the edge of the discharge apertures and to place it at a short distance in front of the latter.

In tubes in which the discharge can only 15 emerge from the cathode shield in the direction remote from the anode the provision of an auxiliary electrode according to the invention is particularly advantageous since it enhances at the same time the auxiliary-anode action of the 20 cathode shield.

Tubes in which the main discharge can only 25 emerge from the cathode shield in the direction remote from the anode but in which the part of the cathode shield adjoining the anode 30 is pierced with one or more igniting holes have the property of igniting immediately after being switched in. In this case the cold cathode is therefore loaded very heavily.

35 Igniting holes are holes provided in the part 30 of the cathode shield adjoining the anode, in such manner that before the ionization of the main discharge path takes place the electrons emitted in front of the cathode can reach the immediate vicinity of the anode or anodes where 40 the potential for ionization of the gas-filling is sufficient to permit the initiation of the main discharge whilst it is practically impossible that coarser particles, for example of emissive material, hurled away from the cathode can reach the anode through the auxiliary apertures. The latter have so small a free diameter relatively to that of the apertures for the passage of the main discharge as to be able to pass but a very small 45 portion of the maximum operating current of the tube.

It affords particular advantages to apply the 50 invention to tubes of this kind and to provide the auxiliary electrode not only in front of the main discharge apertures but to extend it as far as in front of the igniting holes.

The invention will now be set out more fully with reference to the accompanying drawing in which

55 Fig. 1 shows a tube according to the invention in vertical section, and

Fig. 2 is a perspective view of a cathode shield and of an auxiliary electrode according to the invention.

60 Figure 3 is schematic circuit showing the perti-

nent electrical connections to the electron tube of the invention.

In the figures, reference numeral 1 designates the wall of the tube and 2 the activated incandescent cathode which is fastened in the wall of the tube with the aid of cathode leads 4, surrounded by ceramic tubes 16, and ferrochrome caps 6. The anodes 3 are fastened in the wall of the tube with the aid of anode leads 5 surrounded by ceramic tubes 10, and ferrochrome caps 7. The ceramic tubes 10 are sealed at 11 with the wall of the tube. Each of the anodes is surrounded by a gauze screen 8 which is fastened around the ceramic tube 10 with the aid of a sleeve 9. The screen 8 leaves only the front surface of the anode free. A screen 12 having a circular bottom portion is interposed between the anodes. The cathode is surrounded by a cylindrical cathode shield 15, having an oversized cap member 18 secured thereto in a raised position in such manner that the discharge can emerge only from the opening between cap 15 and cap 18 in the direction remote from the anode. The cap 18 of the cathode shield has pierced in it two igniting holes 17. The auxiliary electrode provided in front of the main discharge aperture is designated by 14 and consists of an annular thick wire. In front of the igniting hole are little rings 13, also consisting of thick wire. The rings 13 and the auxiliary electrode 14 are interconnected and connected to the cathode shield by connecting wires 19. The cathode shield is connected to the exterior by means of a leading-in wire 21. The ferrochrome caps 6 of the cathode leads contain a few mercury drops 20 serving as a supply of vapour-forming material. The tube contains, in addition, an argon filling of a few tenths of mm. mercury pressure and can supply a direct current voltage of 110 volts at a current of 25 amps. If the potential of the cathode shield and of the associated auxiliary electrode is maintained floating the tube does not ignite at the full anode voltage. The cathode shield and the auxiliary electrode are connected to a potentiometer of about 3000 ohms at one-third from the cathode end, for example as shown in Figure 3 wherein a potentiometer 40 has one end connected to the anode 3 and the other end connected to the cathode 2, a tapping 41 approximately one-third from the cathode end being connected to the shield 15 and auxiliary electrode 14. The current for the cathode shield starts the flow at a voltage of from 10 to 11 volts. The anode current starts to flow almost simultaneously, the anode voltage then being from 30 to 33 volts. The arc voltage amounts to 10 volts.

What I claim is:

1. A gaseous discharge device comprising an electron-emissive cathode, anode means, a shield surrounding said cathode and having an opening therein, said opening facing away from such anode means for the passage of discharge current in the direction remote from said anode means, and auxiliary electrode means mounted in front of said opening.

2. A gaseous discharge device comprising an electron-emissive cathode, anode means, a shield surrounding said cathode and having an opening therein, said opening facing away from said anode means for the passage of discharge current in the direction remote from said anode means, and a wire-formed auxiliary electrode mounted in front of said opening, the shape of said electrode being substantially similar to the periphery of said opening.

3. A gaseous discharge device comprising an electron-emissive cathode, anode means, a shield surrounding said cathode and having an opening and apertures therein, said opening facing away from said anode means for the passage of a major portion of discharge current in the direction remote from said anode means, said apertures facing toward said anode means for the passage of a minor portion of discharge current in the direction towards said anode means, and auxiliary electrode means mounted in front of said opening and said apertures.

4. A gaseous discharge device comprising an electron-emissive cathode, anode means, a cylindrical shield surrounding said cathode, said shield having an oversized cap member secured in raised position to the end of said shield adjoining said anode means, said cap member defining an annular opening with said shield for the passage of discharge current in the direction remote from said anode means, and an annular auxiliary electrode mounted concentric with said shield and in front of said opening.

5. A gaseous discharge device comprising an electron-emissive cathode, anode means, a cylindrical shield surrounding said cathode, said shield having an oversized cap member secured in raised position to the end of said shield adjoining said anode means, said cap member defining an annular opening with said shield for the passage of a major portion of discharge current in the direction remote from said anode means, said cap member having apertures therein for the passage of a minor portion of discharge current in the direction towards said anode means, and an auxiliary electrode having an annular portion mounted concentrically with respect to said shield and in front of said opening and ring portions mounted in front of said apertures.

6. A gaseous discharge device comprising an electron-emissive cathode, a pair of anodes, said cathode and said anodes being symmetrically arranged, a flat screen disposed intermediate said anodes, a cylindrical shield surrounding said cathode, said cylindrical shield having an oversized cap member secured in raised position to the end of said cylindrical shield adjoining said anodes, said cap member defining an annular opening with said shield for the passage of a major portion of discharge current in the direction remote from said anodes, said cap member having apertures therein for the passage of a minor portion of discharge current in the direction towards said anodes, and an auxiliary electrode having an annular portion mounted concentrically with respect to said cylindrical shield and in front of said opening and ring portions mounted in front of said apertures.
